[57] CLAIM

The ornamental design for a tub for bathing, as shown and described.

DESCRIPTION

FIG. 1 is a top, front, and slightly right perspective view of a tub for bathing embodying my new design;

FIG. 2 is a top plan view thereof;

FIG. 3 is a front elevational view thereof, the rear elevational view being a mirror image of the front side shown;

FIG. 4 is a left side elevational view thereof;

FIG. 5 is a right side elevational view thereof;

FIG. 6 is a cross-sectional view taken along line 6—6 of FIG. 2;

FIG. 7 is a cross-sectional view taken along line 7—7 of FIG. 2; and,

FIG. 8 is a cross-sectional view taken along line 8—8 of FIG. 2.

The broken line representations of holes and slots in FIG. 1—8 are for purposes of illustration only, and form no part of the claimed design.
